L. E. CONNELLY,
STEAM BOILER FURNACE.
APPLICATION FILED FEB. 20, 1918.

1,333,652.

Patented Mar. 16, 1920.

UNITED STATES PATENT OFFICE.

LAWRENCE E. CONNELLY, OF CLEVELAND, OHIO, ASSIGNOR OF ONE-HALF TO WILLIAM C. CONNELLY, OF CLEVELAND, OHIO.

STEAM-BOILER FURNACE.

1,333,652.

Specification of Letters Patent. Patented Mar. 16, 1920.

Application filed February 20, 1918. Serial No. 218,261.

To all whom it may concern:

Be it known that I, LAWRENCE E. CONNELLY, a citizen of the United States, residing at Cleveland, in the county of Cuyahoga and State of Ohio, have invented certain new and useful Improvements in Steam-Boiler Furnaces; and I do hereby declare the following to be a full, clear, and exact description of the invention, such as 10 will enable others skilled in the art to which it appertains to make and use the same, reference being had to the accompanying drawings, and to the letters of reference marked thereon, forming part of this specification.

15 My invention relates to steam boilers and consists in certain improvements in the arrangement of baffle plates hereinafter explained and pointed out, and illustrated in the accompanying drawings in which:

20 Figure 1, is a cross section of a fragment of a mud-drum of a water tube steam boiler showing my improved baffle wall associated therewith.

Fig. 2, is a plan view of a fragment of my 25 improved baffle.

Fig. 3 is a plan view of pieces thereof separated.

Fig. 4, is an end view thereof placed together.

30 Fig. 5, is an enlarged edgewise view of parts shown in Fig. 2.

In these drawings A indicates the mud drum of a water tube steam boiler of the Stirling type; B indicates the rear bank of 35 water tubes, and B' indicates the rearmost row of water tubes of the bank of tubes in front of the bank B.

Behind the mud-drum A I erect a wall E upon the bottom (not shown) of the furnace setting, the upper end of which wall E is in spaced relation to the mud-drum A. From the upper end of the wall E a baffle F extends upwardly and curves forwardly transversely, and in spaced relation to the 45 mud-drum A, through the bank of tubes B and is particularly described as follows, viz:—F' indicates curved plates which are inserted between the tubes B as shown in Fig. 2, the upper ends of which are hooked 50 into clamps f secured on the last or rear

tubes B' of the bank of tubes in front of the bank B; said plates F' extending downwardly in spaced relation to the drum A and terminating in a pocket e in the top of the wall E, where they are embedded in 55 asbestos or other suitable material which will allow relative movement of said plates. Upon these plates F' I secure a series of plates G and G' which are provided with substantially semi-circular recesses adapted 60 to embrace the tubes B' and at the same time overlap each other to prevent the escape of gas between said plates, as shown in Figs. 2 and 4. These plates G and G' are also provided at one end thereof with 65 offset flanges g adapted to overlap the next succeeding plate vertically, as shown in Figs. 1 and 5, so that the baffle thus made up of the plates F' supporting the overlapping plates G and G' efficiently prevents the 70 passage of fire-gas. The overlapping plates G and G' are secured upon the plates F' by means of bolts or screws g' so that they cannot become dislocated.

Having thus fully shown and described 75 my invention so as to enable others to utilize the same, what I claim as new and desire to secure by Letters Patent is:—

1. A baffle for water-tube steam generators consisting of a series of plates placed 80 between rows of boiler tubes, and a series of rectangular plates supported on said first mentioned plates, said rectangular plates having substantially semi-circular recesses in adjacent edges thereof receiving and embracing the boiler tubes, said rectangular plates overlapping each other longitudinally and transversely substantially as described.

2. The combination in a fire-baffle for 85 water tube steam boilers of a bank of tubes; a series of plates between rows of said tubes; and a series of rectangular plates supported on said first mentioned plates, said rectangular plates being shingled and overlapping each other longitudinally and 90 transversely, and having substantially semi-circular recesses in the adjacent edges thereof embracing said tubes, substantially as set forth.

3. The combination in a fire baffle for 100

water tube steam boilers of a bank of tubes, a series of plates between rows of said tubes, a series of rectangular longitudinally overlapping plates having semi-circular recesses in adjacent edges thereof embracing said boiler tubes, each rectangular plate being provided at one end with a flange overlap-

ping the next adjacent rectangular plate transversely of said baffle, substantially as set forth.

10

In testimony whereof I affix my signature.
LAWRENCE E. CONNELLY.

Witness:

J. D. COLLINS.
